UNITED STATES PATENT OFFICE.

GEORGE T. LADD, OF PITTSBURGH, PENNSYLVANIA.

WATER-TUBE BOILER.

1,207,301.

Specification of Letters Patent.

Patented Dec. 5, 1916.

Application filed August 11, 1915. Serial No. 45,031.

To all whom it may concern:

Be it known that I, GEORGE T. LADD, residing at Pittsburgh, in the county of Allegheny and State of Pennsylvania, a citizen 5 of the United States, have invented or discovered certain new and useful Improvements in Water-Tube Boilers, of which Improvements the following is a specification.

The invention described herein relates to 10 certain improvements in the manner of baffling the Milne type of water tube boiler, consisting of upper and lower drums connected by a central set of tubes and two sets or posts of tubes arranged on opposite sides 15 of the central set or nest. It has heretofore been the practice to arrange a baffle against the innermost row of tubes of the set next adjacent to the fire-chamber, so that the products of combustion as they pass from 20 the fire box flow up between the tubes of this set to a plane near the upper drum. The products of combustion then pass over this first baffle and flow down through the space between the first and central set of tubes 25 and along this set of tubes, a baffle extending down from the upper drum alongside the row of tubes on the stack side of such set. This second baffle extends down nearly to the lower end, and the products of combustion pass around its lower end and flow 30 up along the third or stack set of tubes to the stack.

Experience has shown that as the gases flow up along the first set of tubes, those 35 portions in contact with the tubes are cooled and retarded, and the gases intermediate the cooled layers or strata flow more rapidly and that as there is no provision made in the passes for mixing the gases, the stratification 40 thus established is maintained to a greater or less degree during the movement of the gases to the stack. The gases flowing from among the tubes of the first set and over the upper end of the first baffle, 45 move down the space between the first and second sets of tubes and along the tubes of the second set in planes approximately parallel with the lines of flow or stratification established during the flow along the 50 first set of tubes. In passing under the second baffle and up along the tubes of the third set, the stratification originally established is not materially disturbed and the gases escape at a high temperature into the 55 stack.

The invention described herein has 151

its object an arrangement of baffling, which will cause the gases to move through the nest of tubes adjacent to one end and back through the same set intermediate of the 60 ends and a third time adjacent to the opposite end, the gases after each movement transverse of the tubes enter an open space or chamber where the cooled and hot gases can intermingle. 65

The invention is hereinafter more fully described and claimed.

In the accompanying drawing forming a part of this specification is shown a sectional elevation of a Milne type of boiler having 70 my improved baffling applied thereto.

The boiler consists of upper and lower drums 1 and 2, and three sets of tubes 4, 5 and 6 connecting said drums. A horizontal baffle 7 is arranged approximately in line 75 with the top of the fire box and extends nearly to the outer tubes of the first set 4, so that the products of combustion as they flow from the fire box will be caused for the most part to pass between the tubes of this 80 first set into the space or mixing chamber 8 between the first and central set 5. The gases on entering this chamber impinge on the vertical baffle 9 extending from the lower drum up to a point adjacent to the upper 85 drum. A considerable volume of the gases will of course flow up along the tubes of the first set, but after they have passed above the horizontal baffle, their vertical 90 flow will be disturbed by the gases from the mixing chamber moving outwardly or to the left. This outward movement from the mixing chamber 8 being due in part to the draft, but principally to the deflection 95 caused by the inclined baffle 16 forming the upper end of a mixing chamber. By reason of the intersection of the two streams or lines of flow, one parallel and along the tubes and the other at an angle to the tubes, a thorough mixing of the gases will be 100 effected in the space or chamber 10 to the left of the first set of tubes. From this mixing chamber 10 the gases pass in a nearly horizontal direction through the first and central sets of tubes into a mixing 105 chamber 11 formed by spacing the central and third sets of tubes apart. The gases are deflected down as they pass through the central sets of tubes by the baffle 12 extending down from the upper drum along the 110 inner row of tubes of the third set nearly to the lower drum. The gases impinging on

this baffle will be deflected among the central set of tubes where they will mingle with gases flowing down along such tubes. The greatest deflection of the gases in the chamber 11 will be effected by the baffle 13 forming the lower end of said chamber. As the gases pass below the baffle 13 they are caused to move across the central set a third time into another mixing space or chamber 14. From this space the gases flow upward along the tubes of the third or stack set of tubes, and the space between such tubes and the side wall of the boiler setting. If such space is uninterrupted and there might be a tendency for the gases to move from between the tubes into such space, it is preferred to arrange a horizontal baffle 15 at a suitable point to compel lateral diversion among the tubes of the stack set. The efficiency of this mode of baffling is shown by the fact that the temperature of the gases in the stack is materially lower than when the old system was employed.

I claim herein as my invention:

1. A boiler having in combination an upper and a lower drum, three sets of tubes connecting said drum; a baffle arranged at an angle to the first set of tubes and adapted to cause products of combustion from the fire box to flow across the lower ends of the first set of tubes; a baffle arranged between the first and second sets of tubes adjacent to their upper ends and adapted to cause products of combustion to flow transverse of the first set of tubes; a baffle for preventing products of combustion from flowing from between the space between the first and second sets of tubes across the second set of tubes; a baffle arranged between the second

and third sets of tubes adjacent to their lower ends and adapted to cause products of combustion to flow transverse of the second or intermediate set of tubes, and a vertically arranged baffle adapted to prevent the flow of products of combustion transverse of the upper portions of the third set of tubes.

2. A boiler having in combination an upper and a lower drum, three sets of tubes connecting said drums, a baffle arranged on the side of the intermediate set adjacent to the fire box; and a second baffle arranged along the inner row of tubes of the set adjacent to the stack, said baffle extending down from the upper toward the lower drum.

3. A boiler having in combination an upper and a lower drum, three sets of tubes connecting said drum, a baffle arranged on the side of the intermediate set adjacent to the fire box and extending vertically from the lower drum toward the upper drum, a baffle for deflecting the products of combustion across the first set of tubes near the upper portions thereof, a baffle arranged along the inner row of tubes of the set adjacent to the stack and extending down from the upper drum toward the lower drum, and a baffle for directing the products of combustion transverse of the intermediate set of tubes near the lower ends of the latter.

In testimony whereof, I have hereunto set my hand.

GEORGE T. LADD.
